COMBINED BOTTLE AND VIAL

Henry C. Bernard, Mount Vernon, N. Y., assignor to Park & Tilford, New York, N. Y., a corporation of
New York

Application December 8, 1955, Serial No. 39,217

Term of patent 3½ years

(Cl. D58—8)

Fig. 1 is an elevational view of a combined bottle and vial, showing my new design;

Fig. 2 is a top plan view thereof;

Fig. 3 is a view similar to Fig. 1, but showing the cap in spaced position from the bottle and vial; and

Fig. 4 is a view similar to Figs. 1 and 3, but showing the respective elements in separated position.

I claim:

The ornamental design for a combined bottle and vial, substantially as shown.
